UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A HANDLE FOR FORKS, &c.

SPECIFICATION forming part of Design No. 23,720, dated October 23, 1894.

Application filed August 7, 1894. Serial No. 519,698. Term of patent 7 years.

To all whom it may concern:

Be it known that I, CHARLES OSBORNE, a citizen of the United States, residing at New York city, in the county and State of New York, have invented and produced a new and original Design for Handles for Spoons or Similar Articles, of which the following is a specification, reference being had to the accompanying drawings, forming part thereof.

10. Figure 1 is a view of the obverse, and Fig. 2 is a view of the reverse side of the handle showing my design.

15. The leading features of my design are the column-like figures on the sides of the handle, the spaced bud-like figures on the columns, and the rosettes and leaves at the base and top of the handle.

20. Springing, at the base of the shank, from an ornament of a Pompeian character, two threads, or beads, encircled by occasional husks, or calixes, and forming column-like figures swelling as they approach the upper broader part, (being there divided into several lines,) form the edges of the handle and

25. terminate at the top in two rosettes. Between the curves formed by these lines the top of the handle is finished by a conventional honeysuckle ornament. The same figure is repeated on the heel, at the back of the bowl, in addition to the back of the handle being 30 almost identical with the front.

I claim—

1. In a design for a handle for spoons or similar articles, the outline herein shown and described.
2. In a design for a handle for spoons or similar articles, the obverse as herein shown and described.
3. In a design for a handle for spoons or similar articles, the reverse as herein shown 40 and described.
4. The design for a handle for spoons or similar articles herein shown and described.

CHARLES OSBORNE.
